FIRE BRICK FOR CHECKER WORK REGENERATORS

Application filed April 23, 1931. Serial No. 532,356.

The present invention relates to checker work regenerators and has particular reference to regenerators which are built in courses, wherein the courses of the checker work are built up of fire brick having a particular shape and structure.

Fire bricks which have been used heretofore in the construction of checker work regenerator furnaces, as for instance, those used in conjunction with open hearth steel furnaces, have been essentially of two types. In the one type, rectangular bricks were placed in courses with their flat faces disposed upwardly and were held in place by means of notches upon certain of the corners which produced bearing surfaces which cooperated with certain other portions of adjacent bricks whereby the various courses were constructed.

20 A second class of brick has been proposed for use in the construction of checker work which were polygonal in cross section and which contained hollow portions, across which, webs or projections extended. The purpose of these tortuous passages, and projections, was to increase the effective heating surface which was exposed to the gas travelling through the checker work.

Many of the checker works which have been used heretofore possessed certain inherent disadvantages which decreased the heating efficiency and heat transfer of the checker work.

Thus it is well known that regenerator checker works, the courses of which are built up of substantially rectangular bricks presenting flat horizontal surfaces for contact with gases passing thereover, lose their efficiency as regenerators after a short time, since the flat surfaces of the regenerator bricks collect and become coated with a relatively non-conducting and somewhat adherent film of soot, cinders, and the like, which not only prevents effective heat transfer, but also impedes the passage of gas through the checker work.

Where fire bricks having webbed projections are used to build the courses of regenerator furnaces, depositions of soot, and the like, also decrease the heating efficiency

of these bricks. Another disadvantage which has militated against their use has been the excessive breakage to which they are prone. This excessive breakage naturally decreases the quantity of brick which may be reclaimed upon dismantling a checker work, and which can be advantageously used for the construction of other checker works.

By the use of a checker work built according to our invention, an increased area of contact is exposed to gases passing through the checker work and therefore, a greater heating efficiency is obtained.

The disposition of the bricks in the courses, if laid according to our invention, is such that a minimal quantity of soot and the like will remain upon the bricks if deposited thereon, and is also such that any material so deposited is readily swept away by the passage of the gases through the checker work.

We have also provided a fire brick, the shape of which is adapted to decrease the breakage loss and therefore increase the amount of reclaimed brick which may be obtained upon dismantling the checker work or regenerator furnace.

In the drawing:

Fig. 1 is a diagrammatic sectional view showing a checker work in conjunction with a furnace such as an open hearth furnace.

Fig. 2 is a showing of several of the units of bricks placed in position for building up the courses of a regenerator furnace.

The unit brick consists of a fire brick having end faces perpendicular to the side face and faces angularly disposed to the ends and sides. The brick shown in the drawing has four sides or faces which are angularly disposed so that adjacent faces are substantially perpendicular one to the other, and has end faces which are substantially perpendicular to all the side faces. Thus, the brick is composed of four side faces 10, 11, 12 and 13, and two end faces 14 and 15, cutting all the side faces at right angles. End faces 16 are disposed in angular relation to the end faces 14 and intersect two adjacent side faces, such as 10 and 12.

It will thus be seen that since the perpen-

dicular end faces cut all the side faces, and the angularly disposed faces cut the end faces and two adjacent side faces, the edge formed by the intersection of said angularly disposed 5 face and said perpendicularly disposed face, is removed from a line connecting two side edges such as 17 and 18, and substantially parallel thereto.

Since these bricks are to be used in building up checker works, the inclosed angle formed between the plane of the end face 14 or 15 and the plane of the angularly disposed end face 16 is substantially 135° or conversely, the angle between the plane of the angularly disposed face 16 and an upward projection of an end face is substantially 45° . Thus when two bricks are placed with their perpendicular end faces in contact, the angle formed between the converging angularly disposed 10 end faces is approximately 90° and these faces serve as bearing surfaces to receive and support the lower edge 19 of a similar fire brick placed therein. These angles may be varied within certain limits, provided the angles formed by the convergence of the angular faces is substantially the same as that formed by the side of the brick which are not intersected by the angular end face. This would necessitate a different degree of angularity of the end faces 16 on a unit brick.

In Fig. 2, the bricks 20 and 21 have been placed with their perpendicular faces juxtaposed and in contact, and a companion pair of bricks have been spaced therefrom and placed substantially in parallel relation thereto. The brick 22, placed within the angular receiving surface formed by the angularly disposed faces of the bricks 20 and 21 and within a similar notch of the companion pair 25 of bricks rests therein and covers approximately one-half of the surface thus formed and permits the placing of a second brick 23 transversely of the two lower supporting bricks 20 and 21, as indicated by the broken lines, thereby forming with brick 22 a receiving 30 and bearing surface composed of the angularly disposed faces 24 and 25.

In the use of this type of brick in the formation of checker works for regenerative furnaces, substantially parallel courses of the bricks are prepared by laying a series of these bricks end to end with their perpendicular end faces juxtaposed and substantially in contact, the parallel rows being spaced and positioned for receiving transverse rows of bricks placed upon and having bearing contact with the bearing surface formed by the angularly disposed end faces 35 whereby alternate courses of bricks are produced which are substantially perpendicular one to the other.

Courses built up of brick of this type, when placed in a checker work or regenerative furnace, thus present a larger area or surface 40 to the heated gases passing thereover and

therefore to gases to be heated as these come into intimate contact with the bricks and flow therearound. In the ordinary type of checker work used heretofore, the gases impinge upon a flat surface of the brick and thereafter flow in eddy current outwardly from the flat surface whereby there is only a slow movement of the heating gases over other surfaces of the bricks. The present type of brick when built in courses, according to our invention, presents angularly disposed faces in the path of the gases moving thereover and the gases are thereby caused to flow over at least three of the sides of the brick and in close proximity thereto where by a better heat transfer may be maintained.

The courses, when built according to our invention, also present substantially no flat portions or areas which will collect and retain soot, cinders, and the like, which may be carried by the gases and deposited therefrom upon the brick.

We have further prepared a checker work wherein a minimum of precipitated material will deposit upon the face of the brick by providing a bridge wall 26 (Fig. 1), upon which the checker work is built and from which it rises and which is placed advantageously in an angular relation with the horizontal. The particular angle will depend upon the various conditions of working and may extend from a few degrees from the horizontal to as much as 45° therefrom. In order to present as large a portion of the courses of brick to the action of the heating gases from the furnace, the end or rider wall 27 of the checker work slopes angularly from the vertical and toward the source of gas passing therethrough, as shown by the side 28 of the wall 27.

As shown in Fig. 1, as hot gas enters the regenerator 29 from the furnace 30 through the port 31, the gas passes over the rider wall 27 and passes downwardly through the spaces in the checker work and exits at a port conveniently located in an end wall 32, such as at 33.

The various courses of brick are placed upon the bridge wall 26 and are parallel thereto. The composite structure of the checker work, therefore, comprises alternate courses of brick which are all substantially parallel to each other, one group of courses being placed longitudinally of the regenerator and another group of courses being placed transversely thereof.

The checker work, if built upon an inclined bridge wall such as shown at 26, Fig. 1, contains alternate courses of brick which are substantially parallel, the ends of the bricks of one group of courses being continuously displaced from a vertical line as additional parallel courses are placed, while the other group of courses contains a series of courses wherein the side edges of the bricks

are continuously displaced in a vertical line as additional courses are placed. The angular displacement of the bricks in the various courses of a given tier of bricks, from the vertical, is substantially the same as the inclination of the bridge wall to the horizontal. 5 Arrows 34 and 35 indicate the passages in the checker work through which the gas may pass. Thus passages such as 34 are substantially vertical to the bridge wall, while passages 35 are defined by the upper edge of one brick, as indicated at 36 and the lower edge 10 of an adjacent brick placed a brick length therefrom.

15 We claim:—

1. A fire brick having four sides and having angularly disposed faces at its ends each intersecting one end face and two side faces of the brick and each forming enclosed angles 20 of substantially 135 degrees with end faces which are substantially perpendicular to the side faces.

2. A checker work construction comprising parallel courses of brick having side faces 25 and end faces placed end to end thereby forming bearing surfaces from faces each forming a plane surface and each disposed angularly to the end of said brick and intersecting three faces thereof and parallel courses formed 30 from brick placed transversely to said first parallel course and upon the said bearing surfaces formed in said first course.

3. A brick having four sides and having a face on each end, two bearing faces converging toward each other and each intersecting only three faces of the brick, each bearing face being complementary to a bearing face on the immediately adjacent brick of a course of brick laid end to end, forming with 40 the complementary face a substantially V-shaped seat, each end of the brick at the opposite side thereof from the bearing face being provided with convergent faces for engaging in a seat of a transversely arranged 45 course of brick.

4. A checker work construction comprising parallel courses composed of brick placed end to end in a plane angularly disposed to the horizontal, and other parallel 50 courses of brick placed transversely with respect to the said first courses and bearing thereon at the points where the end faces of juxtaposed brick are in contact.

5. A checker work construction comprising parallel courses composed of brick placed end to end in a plane angularly disposed to the horizontal, and other parallel courses of brick placed transversely with respect to the said first courses and bearing upon faces of 55 the brick disposed angularly with respect to the end and side faces.

6. A checker work construction comprising a group of parallel courses of brick in tiers, a second group of parallel courses of 60 brick substantially at right angles to said

first group and placed alternately thereamong in tiers, one group of parallel tiers being composed of brick, the end faces of which project slightly beyond the end face of the underlying brick in the underlying course, the other group of tiers being composed of brick one side of which is offset horizontally beyond the underlying brick in the underlying course. 70

7. A brick having end faces and having 75 the major transverse width of the brick located between the upper and lower margin of the brick, the transverse dimension decreasing above and below the major transverse width, each end of the brick being provided with a bearing face intersecting the adjacent end wall at one side of the major width whereby said bearing face is contiguous to three faces of the brick. 80

8. A fire brick having side faces angularly 85 disposed to each other, a pair of end faces intersecting the side faces, and a face forming a plane surface intersecting an end face and two side faces.

9. A fire brick having side faces angularly 90 disposed to each other, a pair of end faces intersecting the side faces, and a plurality of faces each forming a plane surface and each intersecting one end face and two side faces. 95

10. A fire brick having side faces at right 100 angles to each other, a pair of end faces parallel to each other and perpendicular to and intersecting the side faces, and a plurality of faces each forming a plane surface intersecting an end face and two side faces. 105
